(57) **CLAIM**

The ornamental design for a roofing shingle, as shown and described.

DESCRIPTION

FIG. 1 is a front perspective view of a first embodiment of a roofing shingle.

FIG. 2 is a front view thereof.

FIG. 3 is a back view thereof.

FIG. 4 is a right side view thereof.

FIG. 5 is a left side view thereof.

FIG. 6 is a top view thereof.

FIG. 7 is a bottom view thereof.

FIG. 8 is a back perspective view thereof.

FIG. 9 is a front perspective view of a second embodiment of a roofing shingle.

FIG. 10 is a front view thereof.

FIG. 11 is a back view thereof.

FIG. 12 is a right side view thereof.

FIG. 13 is a left side view thereof.

FIG. 14 is a top view thereof.

FIG. 15 is a bottom view thereof; and,

FIG. 16 is a back perspective view thereof.

The broken lines depict portions of the roofing shingle and form no part of the claimed design.

1 Claim, 12 Drawing Sheets
